UNITED STATES PATENT OFFICE.

ROBERT O. MIDDLETON, OF CAMDEN POINT, MISSOURI.

MECHANICAL TELEPHONE.

SPECIFICATION forming part of Letters Patent No. 336,731, dated February 23, 1886.

Application filed September 18, 1884. Serial No. 143,407. (No model.

To all whom it may concern:

Be it known that I, ROBERT O. MIDDLETON, a citizen of the United States of America, residing at Camden Point, in the county of 5 Platte and State of Missouri, have invented certain new and useful Improvements in Telephones; and I do hereby declare the following to be a full, clear, and exact description of the invention, such as will enable others 10 skilled in the art to which it appertains to make and use the same, reference being had to the accompanying drawings, and to letters or figures of reference marked thereon, which form a part of this specification.

15 My invention has reference to telephones; and it consists in the improvements hereinafter described and explained.

In the accompanying drawings, forming part of this specification, Figure 1 is a side 20 view of my improved telephone, and Fig. 2 is a central sectional view.

A represents a vertical board, which is designed to support the telephone proper, but is isolated therefrom by means of a series of 25 knobs, a. The telephone proper consists of an annular band or section, B, which has secured to its front and rear sides, respectively, diaphragms C D, which form between them a sound-chamber, E.

30 F represents a section secured on the front of the annular band B, and is formed to present the mouth-piece G, contracted toward its inner portion, and an enlarging resonating chamber, H.

35 I represents the line-wire, which passes through a perforation, c, in the board A, and through an opening in the diaphragm C, and is attached to the shank of a pin, J, located centrally in the diaphragm D. The portion 40 of the pin J located in the resonating-chamber H is formed to present a button, d. A tube, K, is located in the band B, with its enlarged portion extending in the direction of the central chamber, E, its smaller or contracted portion projecting beyond the said 45 ring for the attachment thereto of one end of

a flexible tube, L, the other end of which carries a suitable listening-tube, M. A spring leaf or reed, e, is secured at one end in the flaring portion f of the tube K, and extending centrally into the chamber E parallel with the diaphragms C D, and is perforated for the passage of the wire I. The mouth-piece G being constructed and contracted as described, the sound-waves will be directed 50 against the center of the diaphragm D, which, with the wire I, will be vibrated in a manner well understood. The said wire I plays freely through the diaphragm C and reed e; consequently when the said wire is vibrated from 55 the other end of the line the diaphragm D will be vibrated, which vibrations will alternately rarefy and condense the air in the chamber E, so as to positively act on the reed and enable the listener to readily detect, through the tube 60 M, the message. When it is desired to summon the party at the other end of the line, the knob d of the pin J is tapped several times, which will result in the wire I operating the diaphragm of the other instrument. 70

I claim—

1. The combination, in a telephone, of a body portion, an opening therein communicating with a listening-tube, diaphragms C D, suitably secured to the said body portion, a 75 reed secured at one end in said opening, and a line-wire connected to said diaphragm D, substantially as set forth.

2. The combination, in a telephone, of a body portion, an opening therein communicating with a listening-tube, diaphragms C D, connected to said body to form an air-chamber, a reed located in said air-chamber, and a line-wire connected to diaphragm D by pin d, and passing through the reed and diaphragm 85 C, substantially as set forth.

In testimony whereof I affix my signature in presence of two witnesses.

ROBERT O. MIDDLETON.
